COIL HANDLING APPARATUS

George H. Rose, Cleveland, Ohio, assignor to The American Steel and Wire Company of New Jersey, a corporation of New Jersey

Application September 23, 1935, Serial No. 41,807

4 Claims. (Cl. 214—87)

This invention relates to coil handling apparatus and is particularly concerned with the handling of rod bundles in a rod mill.

Referring to the accompanying drawings which illustrate apparatus embodying the principles of the present invention:

Figure 1 is a top view of the apparatus.

Figure 2 is a side view.

Figure 3 is an enlarged section from the line 10 III—III in Figure 1.

Figures 4 and 5 are enlarged sections from the line IV—IV and V—V in Figure 2.

Figure 6 is a section from the line VI—VI in Figure 5.

15 Figure 7 is a wiring diagram.

More particularly, the apparatus includes a rack 1 constructed to receive rod bundles 2 one at a time and position them on their sides in at least partially upstanding positions. These 20 rod bundles may be delivered to the rack from a conveyer of the type including a declining apron 3 which terminates over the rack 1 and over which the rod bundles are dragged by intermittently moved dogs 4. It might be explained at this point that such a conveyer is 25 usually used to carry rod bundles away from the collars by which they are initially formed.

A second conveyer provides a series of spaced traveling hooks 5 arranged to move oppositely 30 past the rack 1 with their ends projecting towards the same. This second conveyer may be the usual type of hook conveyer commonly used around rod mills to carry rod bundles away from the first described conveyer to other 35 departments.

An elevated trackway 6 is arranged to span the space between the rack 1 and the path of the traveling hooks 5. For convenience, this 40 trackway may be mounted on spaced beams 7 which may be themselves supported in any suitable manner, the details of this being omitted to avoid confusion.

A carriage 8 rides the trackway 6, and a shaft 9 projects vertically through this carriage and 45 is journaled by the latter for rotative and vertical movements. The lower end of this shaft 9 is provided with a double-ended hook 10, and its upper end has a cross-head 11 fixed to it above the carriage 8 so that the shaft 9 can rotate while the cross-head does not. Fluid motors 12 are mounted by the carriage 8 parallel with either side of the shaft 9, and the operating rods 12^a of these motors are operatively connected to 50 the cross-head 11, the extreme ends of the latter

sliding on vertical guides 13 which function to guide the cross-head in a vertical direction.

Gearing 14 is arranged on the carriage so as to rotate the shaft 9 while permitting vertical movement of the same, and a rack 15 engages an element of this gearing so that reciprocation of this rack causes rotation of the shaft 9. A fluid motor 16 is mounted by the carriage 8 and its operating rod 16^a is operatively connected to the rack 15. The arrangement of these particular parts is such that for each stroke of the rod 16^a in either direction the shaft 9 is rotated a half-turn, and so that the ends of the double-ended hook 10 on the lower end of this shaft will point toward either the rack 1 or the hooks 5 when the rod is at either extreme of its stroke.

Still referring to the mounting of the shaft 9 by the carriage 8 and to the driving of this shaft 9, it will be noted that this shaft is journaled in a sleeve 9^a which is itself journaled by the carriage 8, the shaft 9 being slidably keyed to this sleeve 9^a so as to permit the required vertical motion. It is this sleeve 9^a which is engaged by the gearing 14 for the purpose of rotating the shaft 9.

An electric motor 17 is mounted at one end of the trackway 6 on a base 18 which is arranged at the end of the beams 7 and likewise supported in any suitable manner. This base 18 also carries a gear box 19 which mounts cranks 20 with their axes at right angles to the traveling direction of the carriage 8. The motor 17 drives the cranks 20 through the gear box 19, the armature shaft of this motor being connected to a brake 21 to provide for quick stopping. 35 Connecting-rods 22 interconnect the cranks 20 with the carriage 8, and it is by this arrangement that the carriage 8 is moved back and forth along the trackway 6 from a position where it is over the rack 1 to a position where it is over 40 the path of the traveling hooks 5.

Flexible hoses 23 interconnect the opposite ends of the fluid motors 12 with a double-acting fluid valve 24 mounted on the inside of one of the beams 7. This valve is provided with interconnected operating levers 24^a and 24^b, and the carriage 8 is provided with a bumper 25 which contacts these two operating levers, the arrangement being such that when the bumper 25 strikes the lever 24^a upon movement of the carriage 8 in that direction the air motors 12 are powered by operation of the valve 24 to raise the shaft 9, and so that when this bumper strikes the lever 24^b fluid is admitted to the opposite ends of the motors 12 by operation of the valve 24 so as to 55

effect lowering of the shaft 9, this latter action occurring when the carriage 8 is moved in the other direction. Furthermore, the arrangement is such that the raising action occurs just after 5 one of the ends of the hook 10 have entered a bundle positioned by the rack 1, and so that the lowering action is effected just after a bundle carried by this hook 10 has been inserted over one of the traveling hooks 5, movement of the 10 hook 10, of course, resulting from movement of the carriage 8.

During the time the carriage is traveling from a position over the rack 1 toward the path of the traveling hooks 5, it is necessary to rotate the 15 shaft 9 so that a bundle carried by either end of the hook 10 can be inserted over one of the traveling hooks. This is done by operation of the shaft 9 so that a bundle carried by either end of the hook 10 can be inserted over one of the traveling hooks. This is done by operation of the fluid motor 16, the opposite ends of this motor being connected by flexible leads 26 to a manually-controlled, double-acting fluid valve 27. Operation of this valve will effect a half-turn of the shaft 9 in whichever direction is required, the valve 27 being supplied with fluid by a line 28 from which a branch line 29 leads to the valve 24. 20 The motor 17 and brake 21 may be manually controlled, and the operator can manually stop this motor long enough to permit him to operate the valve 27 so as to turn the shaft 9. This, however, might introduce an accident hazard, and 25 the present invention provides for the elimination of such.

Now referring to the wiring diagram, it will be noted that the motor 17 is powered by lines 30 and 31 through a relay switch 32. Furthermore, 35 the motor 17 is geared to a drum having conductor segments 33 which are contacted by brushes 34. A master switch which includes a manually operable lever 35 functions when thrown in one direction to close a switch 36 which energizes the 40 solenoid of the relay 32 and starts operation of the motor 17. Soon after operation of the motor 17 is started, one or the other of the segments 33 spans the brushes 34 and thus maintains energization of this relay, these segments and brushes 45 being arranged to shunt the switch 36. As soon as the end of this segment is reached the holding circuit to the relay 32 is broken and the motor 17 stopped. The electromagnetic brake 21 can 50 be connected in the usual manner for application every time the motor 17 is deenergized. The arrangement of the segments is such that their ends are reached every time the motor 17 is operated to such an extent as to bring the carriage 8 to an intermediate position on the trackway 6 regardless of its moving direction. In this manner 55 the carriage is automatically stopped at an intermediate position so as to afford the operator time to effect rotation of the shaft 9, restarting of the motor 17 being effected by a further manual operation of the lever 35.

Also, it is possible for the operator to manually operate the lever 35 so as to start the motor in order to bring the hook 10 over one of the traveling hooks 5 to deposit a bundle on the latter. However, here again an accident hazard is introduced, it being understood that the traveling hooks 5 are generally moving at a constant rate and cannot be stopped by the operator. Therefore, the present invention also provides for 65 automatically effecting synchronous meetings of the hooks 10 and the traveling hooks 5.

For this purpose a switch 37 is arranged in the path of the traveling hooks 5 and each of the latter is provided with a bumper 38 which closes 70 the switch 37 as it passes. This switch 37 is ar-

ranged at the position in advance of the position which each traveling hook must occupy if the hook 10 on the end of the shaft 9 is to meet it properly so as to deposit a bundle on it.

Referring again to the wiring diagram, it will be noted that opposite operation of the manually operable lever 35 will close a switch 39 which is in series with the switch 37. Now when an operator sees one of the traveling hooks coming along onto which he desires to load a bundle, it being assumed that the bundle is already carried by the hook 10 on the end of the shaft 9 and that the latter has been rotated in the proper manner, this operator moves the lever 35 so as to close the switch 39. This will not energize the solenoid of the relay switch 32 until the switch 37 is closed by passage of this particular traveling hook. When this occurs, the relay switch is energized, the motor 17 starts and one or the other of the segments 33 spans the brushes 34. 20 The motor 17 then continues to operate until the end of this particular segment is reached. The apparatus is timed so that during this interval the carriage 8 is moved to a point over the path of the traveling hooks and returned to its stopping position intermediate the ends of the trackway 6. Since the motor 17 is initially energized at exactly the right moment, it of necessity effects a synchronous meeting of the hook 10 with the selected one of the traveling hooks 5.

A summary of the foregoing shows that operation of the apparatus described is practically entirely automatic. Thus, each time a bundle slides over the apron 3 and drops onto the rack 1, the operator moves the manually operable lever 35 so as to cause the carriage 8 to advance to a position over the rack. One or the other of the ends of the hook 10 is then within the bundle and the latter is lifted due to the admission of fluid to the proper end of the fluid motors 12 by the 40 automatic operation of the valve 24, which occurs simultaneously due to the operation of the lever 24^a by the bumper 25. The motor 17 continues to operate so that the carriage 8 is immediately moved to its intermediate position. The 45 operator then has leisure to operate the valve 27 so as to cause rotation of the shaft 9. He then elects an advancing one of the traveling hooks and throws the lever 35 in a direction to close the switch 39. Then, as soon as the switch 50 37 is closed by the advancing hook, the loading action is completed, the bumper 25 striking the lever 24^a so as to operate the valve 24 and thus effect lowering action of the shaft 9 during the period that the carriage 8 is over the path of 55 the traveling hooks and before it begins its return to its intermediate position. Upon its arrival at its intermediate position the carriage 8 is again ready for action due to the fact that the lower end of the shaft 9 is provided with a 60 double-ended hook and, therefore, need not be rotated at this time.

I claim:

1. A device for transferring coils from a rack to traveling hooks comprising an elevated trackway arranged to span the space between said rack and the path of said traveling hooks, a carriage riding said trackway, a vertically movable transfer hook rotatively depending from said carriage, means for moving said carriage along said trackway, means for effecting vertical and rotative movements of said transfer hook, and means responsive to movement of said traveling hooks for controlling the first named means so as to effect 75

synchronous meetings of said transfer hook and said traveling hooks.

2. A device for transferring coils from a rack to traveling hooks comprising an elevated track-way arranged to span the space between said rack and the path of said traveling hooks, a carriage riding said trackway, a vertically movable transfer hook rotatively depending from said carriage, means for moving said carriage along said track-way, means for effecting vertical movement of said transfer hook, the second named means being responsive to movement of said carriage by the first named means to positions over said rack and over the path of said traveling hooks so as to automatically effect raising and lowering of said transfer hook and means responsive to movement of said traveling hooks for controlling the first named means so as to automatically effect synchronous meetings of said transfer hook and said traveling hooks.

3. A device for transferring coils from a rack to traveling hooks comprising an elevated track-way arranged to span the space between said rack and the path of said traveling hooks, a carriage riding said trackway, a vertically movable transfer hook rotatively depending from said carriage, means for moving said carriage along said trackway, means for effecting vertical movement of said transfer hook, the second named means being responsive to movement of said carriage by the first named means to positions over said rack and over the path of said traveling hooks so as to automatically effect raising and lowering

of said transfer hook, means responsive to movement of said traveling hooks for controlling the first named means so as to automatically effect synchronous meetings of said transfer hook and said traveling hooks, means responsive to arrival of said carriage at an intermediate position on said trackway for automatically stopping operation of the first named means, means for rotating said transfer hook, and means for restarting operation of the first named means.

4. A device for transferring coils from a rack to traveling hooks comprising an elevated track-way arranged to span the space between said rack and the path of said traveling hooks, a carriage riding said trackway, a hook-ended transfer shaft projecting vertically through said carriage and journaled by the latter for rotative and vertical movement, a cross-head fixed to the upper end of said shaft above said carriage so that said transfer shaft can rotate, fluid motors mounted by said carriage parallel to either side of said shaft and operatively connected to said cross-head, means for guiding said cross-head in a vertical direction, gearing arranged on said carriage so as to rotate said transfer shaft while permitting vertical movement thereof, a rack engaging said gearing, a fluid motor mounted on said carriage and operatively connected to said rack, a crank mounted at one end of said trackway, a connecting-rod interconnecting said crank and said carriage, and means for rotating said crank.

GEORGE H. ROSE.
